(57) **CLAIM**

The ornamental design for a combined siren and lighthead assembly for a vehicle bumper, as shown and described.

DESCRIPTION

FIG. 1 is a frontal perspective view of a combined siren and lighthead assembly for a vehicle bumper for the vehicle driver side thereof;

FIG. 2 is a front elevational view of a combined siren and lighthead assembly of FIG. 1;

FIG. 3 is a right side view of a combined siren and lighthead assembly of FIG. 1;

FIG. 4 is a left side view of a combined siren and lighthead assembly of FIG. 1;

FIG. 5 is a top plan view of a combined siren and lighthead assembly of FIG. 1;

FIG. 6 is a bottom plan view of a combined siren and lighthead assembly of FIG. 1;

FIG. 7 is a frontal perspective view of a combined siren and lighthead assembly for a vehicle bumper for the passenger side thereof;

FIG. 8 is a front elevational view of a combined siren and lighthead assembly of FIG. 7;

FIG. 9 is a right side view of a combined siren and lighthead assembly of FIG. 7;

FIG. 10 is a left side view of a combined siren and lighthead assembly of FIG. 7;

FIG. 11 is a top plan view of a combined siren and lighthead assembly of FIG. 7; and,

FIG. 12 is a bottom plan view of a combined siren and lighthead assembly of FIG. 7.

The rear views of a combined siren and lighthead assembly for the vehicle driver side and the passenger form no part of the claimed design.

The portions shown in broken lines form no part of the claim design.
